FOOT GUARD

Albert A. Strauss, Pittsburgh, Pa.

Application August 20, 1935, Serial No. 37,053

6 Claims. (Cl. 36—72)

This invention relates to foot guards adapted to be attached to the shoes of workmen to protect the feet from injury by heavy blows produced by falling articles.

5 In mines, quarries and the like, workmen are constantly in danger of having their feet injured by the fall of heavy chunks of coal or rock. In rolling mills and other industrial plants where workmen are required to handle billets and other 10 heavy objects, there is constant danger from the accidental dropping or falling of objects.

Among the objects of the present invention are the provision of an efficient shoe guard which may be readily attached to the shoe, and is normally held in position out of contact with the shoe, or with the ground, so that it does not interfere with the stepping of the wearer but is permitted to yield under the effect of a blow or a falling weight. A further object is to provide 20 means for positively holding or securing the guard against sliding movements on the shoe. A further object is to provide resilient means for normally lifting the guard above the shoe with the bottom edge of the guard raised a short distance 25 above the ground so that the sole of the shoe projects slightly below the guard.

The above mentioned and other objects will appear from the following detailed description in connection with the accompanying drawings, 30 in which—

Figure 1 is a side elevation of a foot guard embodying my invention and showing the same applied to a shoe with the guard in normal position, the upper forward part being broken away 35 to show the lifting spring which resiliently supports the guard above the shoe.

Figure 2 is a perspective view of the guard shown in Fig. 1.

40 Figure 3 is a bottom plan view of Fig. 1, with the forward part of the sole of the shoe broken away.

Figure 4 is a fragmentary sectional view of the forward part of the guard showing a modified 45 form of the lifting spring.

Figure 5 is a sectional view on the line 5—5 of Fig. 4.

Figure 6 is a side elevation of my foot guard applied to a shoe, showing the spring arms which 50 carry the locking or securing clips attached at the upper part of the arch of the guard instead of the bottom, as in Fig. 1.

Figure 7 is a transverse section taken on the line 7—7 of Fig. 6.

55 Figure 8 is a fragmentary side elevation show-

ing a modification of the locking spring supports provided with spurs to engage the heel of the shoe.

Figure 9 is a fragmentary sectional view taken on the line 9—9 of Fig. 8.

Figure 10 is a fragmentary perspective view of 5 one of the spring supporting arms provided with the heel engaging spurs shown in Figs. 8 and 9.

Figures 11 and 12 are fragmentary sectional views of the forward position of my foot guard showing further modifications of the resilient 10 lifting device.

Figures 13 and 14 are side elevation and bottom plan views respectively of a form of my invention having pairs of spring arms attached upon opposite sides of the foot guard which are provided with clips engaging the sole of the shoe adjacent the toe and at the instep. 15

Figures 15 and 16 are side elevation and bottom plan views respectively showing a different arrangement of the supporting spring arms. 20

The body 1 of my foot guard conforms approximately to the shape of the shoe and is formed of any suitable rigid material capable, when formed as an arch, of supporting heavy blows or weights without deformation and is preferably 25 pressed or stamped from a relatively light gage metal sheet. The sheet metal may be made more rigid if desired in the usual manner by means of corrugations or ribs 2.

In order to support the foot guard out of contact with the shoe and also maintain the bottom edges 3 above the ground when in normal position, I provide means for positively fastening the rearward portion of the guard to the sole of the shoe and support the forward portion of the guard yieldingly by means of resilient devices attached to the underside of the guard. When the bottom of the guard rests normally on the ground, there is an up and down sliding movement of the guard over the shoe in walking and the engagement of the bottom edge of the guard with the ground impedes the free movements of the feet. I have overcome these objections by resiliently suspending the guard above the shoe 40 and out of contact with the ground, while permitting the guard to instantly yield and transmit the effect of a blow or falling object directly to the ground. 45

In order to positively support the guard at the rear I provide clips 5 which clamp the opposite surfaces of the sole of the shoe at the instep. These clamps or clips are carried at the free ends of spring tension arms 6, which are riveted at their forward ends to the lower margin of the 50 guard, as indicated at 7. The spring arms 6 are 55

forced outwardly in order to engage the clips upon the sole and hence are under tension to press the clips firmly about the sole. The guard is thus securely anchored to the sole of the shoe and cannot slide up and down in walking. It will be observed that by providing a return curve 6^a adjacent the free ends of the spring arms, the spring tension exerted upon the clips 5 is enhanced, thus securing a firmer locking grip of the clips upon the shoe sole.

In the modification shown in Figs. 6 and 7, the spring arms 6¹ are formed into an integral arch riveted at the center to the arch of the guard. It thus constitutes a reinforcement to the guard throughout this arched engagement. The outwardly curved arms in this form afford an increased cushioning effect in a vertical direction to absorb shocks and blows.

Instead of anchoring the spring arms 6 to the sole at the instep, they may be arranged to anchor at the heel as indicated in Figs. 8 and 9. In this case the upper lip of the clamp may be bevelled as shown at 5^a to wedge between the sole, which forms the base of the heel, and the body of the shoe, in the manner indicated in Fig. 9. The lower lip of the clamp may be replaced by a prong or pin 5^b formed or struck up in the metal below the bevelled lip 5^a. The free ends of the spring arms are thus securely held and anchored to the heel extension of the sole between the lip 5^a and prong 5^b forming the clamp.

The forward portion of the foot guard is resiliently supported above the shoe by spring member fastened to the inner wall of the guard and bearing at its free end upon the toe portion of the shoe. In the form shown in Figs. 1 and 3, a flat leaf spring 10 is riveted at 12 to the guard and projects forwardly with its free end bearing upon the shoe. A cushioning pad 14 of leather or other suitable material may be secured to the spring at the point of engagement with the shoe.

In the form shown in Figs. 4 and 5 the supporting spring is riveted at one side of the guard and in Fig. 12 it is riveted at the lower front edge of the guard. Instead of a flat or leaf spring, I may employ a helical spring 10^a, as indicated in Fig. 11. In each of these arrangements, the guard is yieldingly supported at its forward portion and normally maintained resiliently suspended out of contact with the shoe and with its bottom edge above the ground or floor. The rearward portion of the guard is securely locked or anchored to the sole of the shoe by the clamping members on the free ends of the tension spring arms 6, so that there is no slipping or vertical sliding movement of the guards when the wearer is walking nor is there any dragging of the guard on the ground.

Instead of supporting the guard at the forward end by means of a resilient member 10 or 10^a bearing upon the top of the toe of the shoe, I may provide a pair of spring arms 6^b riveted or otherwise attached to the guard, the arms being provided with clasps or clips 5 having ears or lugs 5^c which project over the edge of the sole upon either side. The front and rear pairs may be made separately and riveted together as indicated on the lower side of Fig. 14, or they may be made integral as indicated on the upper side of Fig. 14.

In Figs. 15 and 16 the front pair of clips are carried by an arcuate spring 6^c riveted to the inner side of the toe portion of the guard. In the arrangements shown in Figs. 13 to 16, the foot guard is resiliently supported and suspended

above the shoe by spring arms clipped to the sole of the shoe so that the guard is entirely supported by the sole with its lower edge above the ground or floor.

The spring arms hold the guard centrally located over the shoe, while the location of the clasps or clips prevent any forward or backward slipping movement.

I have illustrated and described several forms of my invention for the purpose of clearly disclosing it but it will be evident that other modifications and changes may be made within the scope of my claims.

I claim:—

1. A foot guard comprising an integral rigid body adapted to extend over the instep and toe of a shoe, spring tension arms fastened to the rearward portion of said body and provided at their free ends with inturned portions forming clamping devices provided with means to engage the opposite surfaces of the sole of a shoe and resilient means secured to the inner wall of said body and positioned to bear upon the toe of the shoe to thereby yieldingly support said body spaced from the shoe at all points.

2. A foot guard comprising a metallic shield adapted to extend over the instep and toe of a shoe, a pair of spring arms fastened to said shield and carrying clips at their free ends, said clips having projecting members adapted to embrace the upper and lower surfaces of the sole of the shoe to secure the arms against sliding movement on the sole, spring means secured to the inner wall of said shield and bearing upon the shoe to normally hold the shield in spaced relation to the shoe, while permitting the shield to move downwardly toward the shoe under the impact of a blow or the weight of a falling body.

3. A foot guard comprising a metallic shield adapted to extend over the instep and toe of a shoe, a pair of spring arms fastened to said shield and carrying fastening devices at their free ends provided with means for engaging the sole of the shoe and securely holding said ends against sliding movement thereon, and a spring device secured to the inner wall of the shield and adapted to bear upon the forward portion of the shoe to normally maintain the shield spaced from the shoe with its bottom edge above the ground or supporting surface.

4. In a foot guard as set forth in claim 3, said fastening devices being provided with one or more sharp prongs adapted to penetrate the sole or heel of the shoe.

5. A foot guard comprising an arcuate metallic shield adapted to extend over the instep and toe of a shoe, pairs of spring arms fastened to said shield and carrying clips at their free ends adapted to bear against the edge of the sole and having means to prevent sliding or slipping movement thereon, said spring arms supporting the shield resiliently above the shoe and centrally located thereover.

6. A foot guard comprising an arcuate metallic shield adapted to extend over the instep and toe of a shoe, pairs of spring arms fastened to said shield and carrying clips at their free ends adapted to bear against the edge of the sole at the instep and adjacent the toe of the shoe, said clips being provided with ears or lugs adapted to project above and below the sole, said spring arms resiliently supporting the shield above the shoe and centrally disposed thereover.
